Primary Examiner — Jennifer Rivard*Assistant Examiner* — Victoria A. Rielly(74) Attorney, Agent, or Firm — Fenwick & West LLP(57) CLAIM

The ornamental design for a cosmetic housing, as shown and described.

DESCRIPTION

FIG. 1 is a front, top, and right side perspective view of a cosmetic housing;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top side plan view thereof;

FIG. 7 is a bottom side plan view thereof; and,

FIG. 8 is a front side elevational view thereof.

The “dash-dash” broken lines in the drawings are included for the purpose of illustrating environmental structure and form no part of the claimed design. The “dash-dot-dash” broken lines in FIG. 7 depict portions of the cosmetic housing that form no part of the claimed design.
